[57] ABSTRACT

The present invention comprises a new and distinct cultivar of Chrysanthemum, botanically known as *Deodranthema grandiflora*, and referred to by the cultivar name Rage in North America. Rage is distinguished by its bright red floret color and long shelf life.

1 Drawing Sheet

1

BACKGROUND OF THE NEW PLANT

Rage was identified as P89-001 originated from a cross made by Peter S. Hesse in a controlled breeding program at Clearwater Nursery, Nipomo, Calif. 93444, USA.

The female parent of Rage was Lucido (U.S. Plant Pat. No. 6,586), and the male parent was Stop Light (U.S. Plant Pat. No. 5,721). Rage was discovered and selected as a flowering plant in October 1989, at Clearwater Nursery, Nipomo, Calif. by Peter S. Hesse in a controlled Greenhouse environment.

The first act of asexual reproduction of Rage was accomplished in March of 1990, when vegetative cuttings were taken in a controlled greenhouse environment at Clearwater Nursery, Nipomo, Calif., by technicians working under the direction of Peter S. Hesse.

Horticultural examination of controlled flowerings of successive plantings has shown that the unique combination of characteristics as herein disclosed for Rage are firmly fixed and are retained through successive generations of asexual reproduction.

Rage has not been observed under all possible environmental conditions. The phenotype may vary significantly with variations in environment such as temperature, light intensity and day length.

The following observations, measurements and comparisons describe plants grown in controlled greenhouse environments at Clearwater Nursery, Nipomo, Calif. Unrooted cuttings were directly stuck into 6.5 inch pots and grown in a controlled environment under the natural temperature and day length prevailing June 1990 to December 1992.

The following traits have been repeatedly observed and are determined to be basic characteristics of Rage which, in combination distinguish this Chrysanthemum as a new and distinct cultivar.

1. Flat Capitulum Form
2. Daisy Capitulum Type
3. Very bright red ray florets under fluorescent lights.
4. Shiny green foliage color.
5. A diameter of 7.8 cm across the face of the capitulum.
6. An average of 9.0 flowers per break.
7. Excellent upright spreading habit with an average of 5.2 breaks after a single pinch.
8. An average flowering response to 59 days from the start of short days.

2

DESCRIPTION OF THE PHOTOGRAPH

The accompanying photograph shows typical inflorescence and leaf characteristics of Rage with the colors being as nearly true as possible with illustrations of this type. The photograph shows Rage grown as a pinched spray pot mum with five (5) cuttings in a 6.5 inch pot.

DESCRIPTION OF THE PLANT

Of the commercial cultivars known to the inventors, the most similar in comparison to Rage is the cultivar identified as Lucido (U.S. Plant Pat. No. 6,586). Reference is made to Table I which compares certain characteristics of Rage to the same characteristics of Lucido.

TABLE I

CHARACTERISTIC	RAGE	LUCIDO
CAPITULUM FORMS	Flat	Flat
CAPITULUM TYPE	Daisy	Daisy
DIAMETER ACROSS FACE	7.8 cm	7.0 cm
BRANCHING PATTERN	Upright	Upright
BREAKS/PINCH	Spreading	Spreading
HEIGHT IN 6.5" POT	5.2	5.4
WITH 1-2 APPLICATIONS B-9	16-17 Inches	16-17 Inches
DISC FLORETS		
DISC FLORET COLOR	13A	13A
NO. OF DISC FLORETS	Many	Many
LENGTH OF DISC FLORETS	ca 0.72 cm	ca 0.64 cm
RAY FLORETS		
COLOR		
FRONT: fully expanded	46A	46A
FRONT: unfolded ray florets	46A	46A
BACK: fully expanded	172B	46B
outer ray floret		
NUMBER	33.4	28.8
SHAPE	Elliptic	Elliptic
LENGTH	3.7 cm	3.3 cm
WIDTH	1.1 cm	0.85 cm
TOTAL NUMBER OF FLOWERS/BREAK	9.0	12.6
LEAF		
COLOR:	Front: 147A Back: 147B	Front: 147A Back: 147B
MATURE LEAF LENGTH:	9.9 cm	9.03 cm
MATURE LEAF WIDTH:	5.7 cm	4.56 cm

Rage is similar to Lucido in the flat capitulum form and the daisy capitulum type. The diameter across the capitulum is essentially the same. Rage has a more upright habit than Lucido. The Number of breaks per pinch is essentially the same for Rage and for Lucido. Disc floret color is also similar. One big difference be-

tween Rage and Lucido is the brightness of the red ray floret color. This is particularly noticeable when both plants are placed side by side and compared under fluorescent lights. Lucido appears darker red and more towards blue or black. Because Rage has more background yellow pigment in the floret, Rage appears brighter red more towards orange. This improves the floral display of Rage at the super market. Rage has more substance than Lucido's ray florets. Rage has more ray florets per capitulum than Lucido. This gives 10 Rage a better shelf life and the brighter red color makes Rage a unique red daisy pot mum.

THE PLANT

15

Classification:

Botanical.—*Dedranthema grandiflora*. Cultivar name: Rage.

Commercial.—Flat daisy to be grown as a 4.5" to 6.5" CBR mum.

Inflorescence:

Capitulum.—Form: Flat. Type: Daisy. Diameter across face: 7.8 cm.

Ray florets.—Color: Red (general tonality within a distance of three (3) meters). Front: Fully expanded outer ray floret 46A. Front: Unfolded ray florets in center of flower 46A. Back: Fully expanded outer ray floret 172B. Front Bud

Stage: Unexpanded outer ray floret. Back Bud Stage: Unexpanded outer ray floret. Shape: Eliptic.

Corolla of disc florets.—Color: Yellow 13A.

5 Reproductive organs:

Androecium.—Present in disc floret only.

Gynoecium.—Present in both ray and disc florets.

General appearance:

Height.—When grown in a 6.5 inch pot with 1-2 applications of B-NINE TM at the rate of 2500 ppm, the total plant height from the bottom of the pot may be maintained at 16-18 inches. When grown in a 4.5 inch pot with 1-5 applications of B-NINE TM at the rate of 2500 ppm the total plant height from the bottom of the pot may be maintained at 10-12 inches. Branching pattern: Upright and spreading with an average of 5.2 breaks when grown with one pinch as a spray pot.

Foliage.—Color: (upper surface) 147A. Color: (lower surface) 147B. Shape: (see photograph).

What is claimed is:

1. A new and distinct Chrysanthemum plant substantially as herein described and shown, characterized by its bright red color and excellent upright spreading habit.
